DESIGN FOR A BRIDGE FOR AN OPHTHALMIC MOUNTING

Edward M. Splaine, Southbridge, Mass., assignor to American Optical Company, Southbridge, Mass., a voluntary association of Massachusetts

Application October 26, 1936, Serial No. 65,516

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for a Bridge for an Ophthalmic Mounting, of which the following is a specification, reference being made to the accompanying drawing, forming a part thereof.

Fig. I is a front perspective view of a bridge for an ophthalmic mounting showing my new design;

Fig. II is an enlarged front view of the same; Fig. III is a plan view of Fig. II; and

Fig. IV is an enlarged sectional view of Fig. II taken on line IV—IV and looking in the direction of the arrows.

The characteristic features of my design reside in the provision of a bridge member formed of two separate slender bar-like members, one secured above the other. The upper bar-like member is arched to a spaced relation with the lower bar-like member centrally thereof to interrupt the

upper contour of the bridge so as to give a crest effect. The superimposed bar-like members are both curved rearwardly throughout the central main bridge portions thereof to substantially the same curvature, the upper bar-like member being provided with end portions which turn forwardly and upwardly. The lower bar-like member turns downwardly and curves forwardly in substantially a vertical plane from points adjacent the ends of the main bridge portion. The bar-like members are relatively thin as compared to their width and the main bridge portions are so formed from said bar-like members that their thin edges only are visible when the bridge is viewed from the front. The bar-like members are shaped and proportioned to blend with each other to produce a balanced effect when in position of use.

I claim:

The ornamental design for a bridge for an ophthalmic mounting, substantially as shown and described.

EDWARD M. SPLAINE.
